His attys.

UNITED STATES PATENT OFFICE.

WILLIAM M. GORE, OF TOLEDO, OHIO.

COMBINATION TERMINAL BOX AND FIXTURE-STUD.

1,287,985.

Specification of Letters Patent. Patented Dec. 17, 1913.

Application filed September 1, 1912. Serial No. 120,288.

To all whom it may concern:

Be it known that I, WILLIAM M. GORE, a citizen of the United States, and a resident of Toledo, in the county of Lucas and State of Ohio, have invented a certain new and useful Combination Terminal Box and Fixture-Stud; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to terminal boxes or plates for electric wiring and has for its object the provision of an improved arrangement and manner of connecting a fixture stud thereto, whereby the box and stud may be used together or separately as desired.

The invention is fully described in the following specification, and while, in its broader aspect, it is capable of embodiment in numerous forms, a preferred embodiment thereof is illustrated in the accompanying drawing, in which—

Figure 1 is a perspective view of a terminal box and fixture stud embodying the invention in assembled relation. Fig. 2 is a perspective view of the fixture stud member removed from the box, and Fig. 3 is a sectional view of the invention attached to a ceiling or wall as it may appear in use and with parts in full.

Referring to the drawings, 1 designates a terminal or outlet box of the type generally used and which may be made in numerous shapes and sizes. The side walls of this box are usually provided with knock-outs 2, and the top 3 is provided with a central opening 4. Around this opening are provided a set of apertures 5, usually four in number, for receiving retaining screws, and arranged in equidistantly spaced circular series. The top 3 is also provided with other apertures 6, which may serve to receive retaining screws.

The fixture stud 7 projects from a circular plate or flange 8 and this flange is provided on its periphery with ears 9, which, when the stud 7 is projected through

the opening 4 with the plate 8 resting on the outer side of the bottom 3, are intended to register with and project into the apertures 5. The ends of the ears 9 may be clenched around an edge wall of the apertures to retain the fixture stud and terminal box in assembled relation, to facilitate a handling thereof.

When the terminal box is attached to a wall or ceiling the plate 8 of the fixture stud is disposed between the article to which attached and the top 3 of the terminal box 70 so that when the retaining screws are inserted through the apertures 6 and into such article the fixture stud flange is securely clamped in position. It is evident that the clamping of the fixture stud plate 70 between the wall and terminal box and the projecting of the ears 9 into the apertures 5 both serve to rigidly hold a fixture stud against a turning relative to the box during the connecting of a fixture 2 or a disconnecting of the same from the stud.

It is evident that a terminal box and fixture stud embodying my invention are capable of being easily and quickly assembled when it is desired to use the two 80 in combination and that when assembled and the box is attached to a wall or ceiling, the fixture stud is firmly held in position.

I wish it understood that my invention is not limited to any specific construction, arrangement or form of the parts as it is capable of numerous modifications without departing from the spirit of the claim.

Having thus described my invention, 90 what I claim as new, and desire to secure by Letters Patent is,—

The combination with a terminal box having its top provided with a fixture stud opening and with a plurality of apertures 95 around said opening, of a fixture stud projected into the box through said opening and having a plate at one end which bears flat against the outer marginal rim of said opening and has ears projected into said 100 apertures and in retaining engagement with the walls thereof.

In testimony whereof I have hereunto signed my name to this specification.

WILLIAM M. GORE.
